[57] CLAIM

The ornamental design for a garment bag, substantially as shown and described.

DESCRIPTION

FIG. 1 is a front elevational view of a garment bag showing our new design;

FIG. 2 is a rear elevational view thereof;

FIG. 3 is a top plan view thereof with the shoulder strap omitted;

FIG. 4 is a bottom plan view of FIG. 3; and

FIG. 5 is a left side elevational view of FIG. 3, the other side being a mirror image thereof.
